US0D1067089S

(12) **United States Design Patent** (10) **Patent No.:** **US D1,067,089 S**
(45) **Date of Patent:** **** Mar. 18, 2025**

(54) **SECURITY TAG**

(71) Applicant: **Sekura Global IP LLP**, Colchester (GB)

(72) Inventors: **Russell Napthine**, Colchester (GB); **Tim Pryce-Hall**, Colchester (GB)

(73) Assignee: **Sekura Global IP LLP**, Colchester (GB)

(**) Term: **15 Years**

(21) Appl. No.: **29/792,406**

(22) Filed: **Mar. 28, 2022**

(30) **Foreign Application Priority Data**

Oct. 1, 2021 (GB) 6168287
